STACKING DEVICE

John F. Peters, Leonia, N. J., assignor to American Can Company, New York, N. Y., a corporation of New Jersey

Application September 17, 1931, Serial No. 563,321

15 Claims. (Cl. 271—87)

The present invention relates to a stacking apparatus and has particular reference to an apparatus adapted to receive blanks or other similar articles from a source of continuous supply, as from a forming, cutting or blanking machine, and arranging the blanks in stacked formation in a magazine.

The principal object of the invention is the provision of an apparatus of simple and novel design for receiving blanks or other flat-sided articles in successive, untimed order and arranging them in stacked formation within a magazine.

An important object of the invention is the provision of an apparatus of the character described wherein the blanks as they are successively received from the source of supply are initially advanced toward the magazine by a feeding device and are then engaged, transferred and freed from the action of the primary feeding means and stacked in the magazine so as to avoid scratching or unnecessary rubbing of the blanks.

An important object of the invention is the provision of holding or retaining elements connected with an apparatus of the character described wherein the blanks, after being positioned in the magazine are retained in vertical stacked position and are prevented from moving backward or interfering with further movements of succeeding blanks.

Numerous other objects of the invention will be apparent as it is better understood from the following description, which, taken in connection with the accompanying drawings, discloses a preferred embodiment thereof.

Referring to the drawings:

Figure 1 is a side elevation of an apparatus embodying the present invention, parts being broken away and parts being shown in section;

Fig. 2 is a fragmentary elevation of the stacking mechanism as applied to the machine disclosed in Fig. 1;

Fig. 3 is an enlarged fragmentary plan view of one of the stacking devices, as viewed substantially along the line 3—3 in Fig. 2;

Fig. 4 is a transverse sectional view taken substantially along the broken line 4—4 in Fig. 3;

Fig. 5 is a longitudinal sectional view taken along the line 5—5 in Fig. 3;

Figs. 6, 7, and 8 are transverse sectional views taken at different positions through the stacking apparatus, illustrated in Fig. 3, these sectional views being taken substantially along the broken lines 6—6, 7—7, and 8—8 of that figure; and

Fig. 9 is a transverse sectional detail taken substantially along the line 9—9 in Fig. 1.

A preferred form of apparatus for exemplifying the present invention is illustrated in the drawings as comprising stacking devices connected to a machine for producing a succession of flat-sided articles. These stacking devices are particularly adapted to stacking end or recovery pieces or blanks as produced in scroll shears or blanking presses and, accordingly, sufficient of the principal working parts of such a machine are shown. Such a press, in addition to the usual strip forming scroll shear dies, also uses cutting dies for operating at the side edges of the sheet as fed through the shear dies and a flat recovery end blank is produced at each side of the press at each operating stroke. The devices or stacking apparatus referred to, one at each side of the press, receive and stack these blank pieces.

Each stacking apparatus receives its blank from an inclined chute into the upper end of which the cut blanks fall from the dies and through which they move down by gravity. A helical screw or conveyor is preferably embodied in each device and the blank passing from the lower end of the chute moves into the upper zone of the screw which engages and advances it at right angles and in upright position toward the receiving and stacking magazine associated therewith.

Each helical screw is rotated at a constant speed and as successive blanks reach the discharge end of the screw, an auxiliary feeding device comes into operation. Such a device embodies a pusher which moves forward at a greater speed of travel than the advancing blank after it has been brought down in position behind a blank. This rapidly advancing pusher thereupon engages the blank at its rear and forces it from the end of the screw, depositing it into the magazine.

Holding devices are disposed on opposite sides of the entrance of the magazine and these are engaged and depressed by the blanks as they enter the mouth of the magazine. The blanks are forced just beyond these stop members which snap into position back of the rearmost blank and prevent its backward or return movement at the same time holding it out of engagement with the end of the helical screw. This prevents scratching or bending of the blank by the screw and at the same time allows the proper placing of successive blanks into their stacked position.

At the forward end of the magazine a yielding or slideable finger is used to rest against the front face of the stack and hold the blanks at that region of the magazine. This finger slides along a rod under the resistance of a friction brake,

thus maintaining a solid stacked condition within the magazine.

A scroll shear press capable of providing a continuous supply of blanks for the stacking devices may comprise a table 21 over which sheets 22 of tinplate or other suitable material are advanced. The usual feeding mechanism for this purpose may be used and since it forms no part of the present invention it is omitted from both 10 drawings and description. Table 21 is secured at its forward end to a frame 23 mounted on side frames 24, the table being partly carried by a rear frame 25. A base 26 provides a unit support for these frame parts. The frame 23 is joined 15 with the usual yoke frame 27 having slideways or grooves 28 in which the usual movable slide 29 operates.

The regular strip cutting members will not be considered, it being understood that operations 20 of that character may be performed as desired. Stationary cutting dies 31 for producing the recovery end blanks are roughly indicated in Fig. 1, these being carried in the frame 23 and disposed in the path of travel of the sheets 22 as they 25 move through the shear press. These dies 31 co-operate with movable punch members 32 carried on the slide 29 and produce end or recovery pieces 35, there being a blank 35 cut from each side of the sheet during each regular shearing 30 operation.

Chutes 36 are provided and located adjacent the sides of the shearing press, each chute being secured at its upper end by a bracket 37 projected inwardly from a side frame 24 and at its 35 lower end by a suitable bracket 38 similarly mounted. An inclined plate 34 guides the end piece 35 in the top of the chute. A separate stacking unit 41 is located on each side of the machine, its entrance end communicating with 40 the delivery end of its associated chute.

The movement of blanks into and through each stacking device, is in the same direction, this being toward the left as viewed in Fig. 2. This arrangement enables one operator on that side of the machine to remove blanks from both 45 devices. The two stacking units 41 are disposed on different levels (Fig. 1) and are located in different vertical positions so that interference between stacks is avoided.

50 The stacking units are identical in construction, the only variation between them relating to their location and to the supports for various parts thereof.

A magazine 45 constitutes a part of each stacking unit and is formed by a pair of spaced angle irons or rails 46, 47 which have lower legs 48, 49 (Figs. 2, 3, 4, and 8) extending inwardly toward each other, these lower legs being located within the same plane.

60 The magazine rails are mounted upon bent projecting arms 51 carried by the base 26. Side walls 52, 53 formed in the respective angle irons constitute lateral guiding elements for the blanks 35 when in the magazine. Rounded supporting 65 ridges 54, 55 formed in the rail 46 and a ridge 56 formed in the rail 47 provide a three-point support for each blank. This insures more precise stacking position.

As a blank 35 is cut from a sheet, it falls upon 70 and into its inclined chute 36 positioned directly beneath being guided by the plate 34 (Fig. 9). Each blank 35 as cut is turned into a vertical position by engagement with an inclined surface 33 of the die 31 and slides downwardly into a 75 helical screw conveyor 59 mounted at the right-

hand end (as viewed in Fig. 2) of its associated magazine 45. Each screw has a continuous tapered helical wall 61 carried on a horizontal shaft 63. The smaller diameter of the screw is first engaged and as the blank advances laterally 5 more wall surface comes into contact with the blank giving it increased support as it approaches the mouth of the magazine.

Each shaft 63 is directly journaled in a bearing 64 and indirectly journaled in a bearing 65 10 both bearings being formed in a frame 57 carried on the projecting end of a bracket 58 formed integrally with the frame 25. As illustrated in Fig. 4, the feeding position of each blank 35 within the screw is with its bottom edge at an angle 15 to the horizontal and above the horizontally disposed shaft 63 along which it moves.

Shaft 63 and the helical screw 59 are continually rotated by a sprocket 66 (Figs. 3 and 5) secured to the shaft adjacent the bearing 64. A 20 chain 67 operates over this sprocket 66 and also over a sprocket 68 (Fig. 2) carried on a horizontal shaft 69 journaled in bearings 71 formed in the rear frame 25. Since there are two shafts 63 and two sprockets 66, one for each magazine, 25 there are two corresponding sprockets 68 and two chains 67. The two sprockets 68 are both mounted upon the single shaft 69. The shaft 69 may be continually rotated from the driving parts of the scroll shear press, a sprocket 75 (see also 30 Fig. 1) being mounted on the end of the shaft for this purpose. A chain 76 operates over the sprocket 75 and also over a sprocket 77 mounted on a drive shaft 78 journaled in bearings 79 formed in the side frames 24. Suitable rotation 35 of the drive shaft 78 may be imparted through the intermediary of a drive pulley 81 mounted on one end of the shaft.

Each spaced section of the wall 61 of the helical screw is sufficiently close to an adjacent section 40 to retain each blank 35 in substantially vertical position, the rail 46, which is projected in front of the magazine, assisting in holding the blank as it advances longitudinally of the shaft 63. In such position it moves into the entrance end 45 of the magazine, the last section 54, 55, 56 of the angle irons 46, 47. The blank is thereupon engaged by a pusher device which will now be described.

The pusher device comprises a plate 91 mounted 50 on the forward end of a stud 92 carried in the outer end of an arm 93 having both longitudinal and up and down or rocking movement. The arm 93 is rocked back as a blank 35 passes along the helical conveyor and in such position 55 its plate 91 is held above and out of the path of travel of the blank. When rocked in the reverse direction the arm 93 moves its plate downwardly and in back of the blank 35 (Fig. 4). The arm 93 now begins its longitudinal movement parallel to the axis of the shaft 63 and this action carries the plate 91 with its engaged blank 60 toward the left (Fig. 3).

The arm 93 (Figs. 3, 6, and 7) is secured to 65 one end of a horizontally disposed shaft 94 which extends through a slide block 95 in which it oscillates. This block is carried by and has sliding movement relative to an extension 96 of the frame 57. The slide block 95 is formed with lateral projections 97 which are engaged by shoudered guide plates 98 secured to the frame part 70 98 by bolts 99.

The block 95 is moved back and forth within its guideways by connection with an actuating cam, best illustrated in Fig. 3. The upper cen- 75

tral part of the block is transversely slotted at 111, and a pivot block 112 is slideably disposed within the slot. This block 112 carries a pin section 113 (Figs. 3 and 7) which provides a pivotal connection for one end of a lever 114 mounted for oscillation on a shouldered stud 115 threadedly engaging the frame 57. The opposite end of the lever 114 carries a stud 116 upon which a cam roller 117 is rotatably mounted.

10 A barrel cam 121 (Figs. 3 and 5) is provided with a cam face 122 against which the cam roller 117 is adapted to operate. A floating guide pin 125 (see also Fig. 6) is pivotally connected at 126 to the lever 114 and has sliding movement 15 within a plate 127 bolted to the side of the frame 57. A spring 128 is mounted on the pin 125 and is interposed between the lever 114 and the plate 127. This spring yieldingly holds the lever in proper position so that its roller 117 engages the 20 cam surface 122 of the cam 121.

The cam 121 (Figs. 3 and 5) has an integral sleeve part which extends adjacent its cam face side to provide a tubular section 141. Sprocket teeth 142 are formed along the opposite edge 25 of the cam and these provide a driving connection for rotating the cam. This cam with its tubular extension 141 is loosely mounted on an extended end section of the screw shaft 63, providing the intermediate bearing for the shaft in 30 the bearing 65.

A cam 145 is mounted on a reduced end of the sleeve section 141 outside of the bearing 65, and is held in fixed adjusted position by a set screw 146. This cam 145 controls a timed, oscillation movement of the shaft 94 and its arm 93 as will be presently described.

The cams 121, 145 are continually rotated by chain connection with the sprocket teeth 142, a chain 151 (Fig. 2) operating over the sprocket 40 teeth for this purpose. This chain 151 (Fig. 2) also operates over a sprocket 153 secured to the shaft 69. Since each magazine has its own cam drive and cam teeth 142, there are also two sprockets 153.

45 It will be observed by reference to Figs. 3 and 5 that the sprockets 66, 142 are of different sizes. This is for the purpose of effecting a different rate of rotation between the shaft 63 with its helical feed screw 59 and the cams 121, 145.

50 The propelling rate of travel of a blank carried in the helical screw is relatively slower than the propelling movement of the pusher plate 91 which means that the blanks are quickly removed from the influence of the screw and placed into the 55 mouth of the magazine. This prevents scratching or bending of the blanks.

The oscillation of the shaft 94 and its arm 60 93 under the control of the cam 145 is effected by a combination of loose connections, best illustrated in Figs. 3 and 6. One end of the shaft 94 beyond the slide 95 is formed into a square projecting section 155 which extends through a tubular sleeve 156. This sleeve can oscillate within a bearing 157, formed in a housing 158 which 65 is secured by screws 159 to a side wall of the frame 57. The sleeve 156 is shouldered inside of the housing 158. This shoulder engages the bearing 157 and cooperating with a collar 160 held on the sleeve exterior of the bearing, prevents lateral shifting of the sleeve within the 70 housing. Inside of the housing, the sleeve is further enlarged to provide a head section 161.

This head is formed with a finger extension 162 which is engaged by a roller 163 carried in 75 a bifurcated end 164 of a lever 165 pivoted on a

stud 166 carried by the housing 158. The opposite end of the lever 165 is also bifurcated as at 167 and a roller 168 is rotatably mounted therein. This roller 168 normally engages the peripheral cam wall of the cam 145.

The housing 158 is formed with a tubular extension 171 in which a slide pin 172 is located. The inner end of the pin engages a shoulder 173 also formed in the head 161 of the sleeve 156. This pin extends through a tubular bore 175 formed in the extension, this bore being sufficiently large to provide a sliding fit for an enlarged collar section 176 formed adjacent the inner end of the pin. The pin 172 slides freely in and out but is prevented from turning on its axis within the bore by a spring pressed button 177 engaging within a slot 178 formed in the periphery of the collar section 176. The button 177 is backed up by a spring 179 located within a lateral bore 181 formed in the extension 171 and 20 confined in position by a screw nut 182.

A helical spring 183 is also located in the bore 175, this spring surrounding the pin 172 and engaging the collar section 176 at one end and a threaded collar 185 at the opposite end. A head 186 is preferably pinned to the outer end of the pin 172.

25 A stop sleeve 187 is disposed on the pin 172 and inside of the spring 183 and forms a limit stop for the pin collar 176 to limit outward movement of 30 the pin.

The spring 183 forces the pin 172 inwardly and holds it against the shoulder 173 of the head 161. This spring operating through the parts 161, 165 holds the roller 168 against the cam 145. As the high section of the cam engages the roller 168 the lever 165 is oscillated about its pivot center and rocks the sleeve 156 correspondingly so that the shaft 94 is oscillated within its slide 95. This rocking movement of the shaft lifts the plate 91 40 out of the path of travel of the blanks 35 (see dotted line position in Fig. 7). As the high section of the cam passes the roller 168 and its low section comes opposite, the spring 183 causes a reversed rocking movement of the parts just described and the plate 91 is moved from the dotted line position (Fig. 7) into the full line position. In this latter position the plate 91 is directly behind an advancing blank 35. Upon forward movement of the slide 95 through the influence 50 of its cam 121, the plate engages the blank, removes it from the helical screw and positions it into the magazine.

The holding devices for preventing return movement of a blank when the pusher plate 91 leaves it in the magazine are illustrated in detail in Figs. 3 and 8. These comprise spring pressed buttons 191, each button having an inclined face 192. Each button is slideably held within a barrel 193 one barrel being inserted in an opening in the 60 side wall 52 of the rail 46, the other barrel being similarly mounted directly opposite in the wall 53 of the rail 47. An enlarged head 194 formed on the button 191 normally rests against an inner wall of the barrel and limits the projection of the 65 inclined end projecting in the path of blanks as they are brought therein. A spring 195 held within the barrel 193 by a screw nut 196 extends within a bore 197 in the button and provides the yielding element for that member.

70 As a blank 35 is moved forward by the pusher plate 91, it engages the inclined faces 192 of the yielding buttons 191 pushing them back to permit passage of the blank whereupon the spring 195 of each button returns it into projected and 75

blank holding position. More than one blank 35 may come into the action of the helical screw 59 during two successive forward movements of the plate 91. Two or more blanks depending on how 5 they come from the feed chute may therefore reach the entrance end of a magazine before engagement and removal by its pusher plate. This variation, however, presents no difficulty and whatever blanks are in position will be stacked 10 with each forward movement of the plate 91.

Provision is made for holding the stack of blanks 35 in proper stacked position within each magazine regardless of the actual number in the magazine at a given time. For this purpose the 15 foremost blank within the magazine is engaged by a finger 201 (Figs. 3 and 4) which extends into the magazine and which is formed with a hub 202 adapted for sliding movement along a bar 203 carried in brackets 204 (see also Fig. 2) 20 mounted upon plates 205, secured to the bottom leg 48 of an angle iron 46.

In the beginning of the stacking operation the finger 201 and its hub 202 are arranged at the right-hand side (Fig. 2) of the magazine, this 25 being adjacent the mouth of the magazine. As the blanks 35 begin to accumulate in the magazine, the foremost blank moves against the finger 201 and thereafter with each advance of the blanks, finger and hub move toward the left, the 30 latter sliding on the bar 203. It is the incoming blanks that cause this movement and, therefore, the combined holding action of the finger 201 and the stop buttons 191 preserves a smooth and uniform stack. An operator can remove any quantity 35 of blanks at any time without requiring any cessation in stacking.

A friction device is provided in each magazine for preventing an uncontrolled or too rapid sliding movement of the finger 201 relative to its associated rod 203. This comprises a pipe 206 (Figs. 40 3 and 4) threadedly engaged at 207 within the hub 202. This pipe projects upwardly at an angle and provides a housing for a friction pin 208 slidably disposed within the pipe and held under the yielding action of a spring 209 so that one end 45 of the pin frictionally engages the rod 203. A set screw 211 is threadedly engaged within the upper end of the pipe and holds the spring under proper compression preventing displacement of spring 50 and pin. With this frictional feature the finger is easily moved by hand or by the blanks but at other times remains in place.

It is thought that the invention and many of its attendant advantages will be understood from 55 the foregoing description and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A blank stacking mechanism comprising in combination a magazine, feeding means for conveying single blanks in succession toward said magazine, a pusher device for removing said blanks from said feeding means and for placing them in stacked formation within said magazine, means for moving said pusher device into and out 70 of the path of the blanks, means for moving the pusher device in said path to propel the blanks, and holding devices for engaging the stacked blanks and holding them away from said feeding means.

2. In a blank stacking mechanism the combi-

nation of a magazine, a rotating helical screw for conveying blanks in spaced upright position toward said magazine, a reciprocating pusher device for engaging behind a said blank as it is conveyed by said screw and moving it into said 5 magazine, means for moving the pusher device into and out of the path of the blanks and holding devices disposed in said magazine for engaging behind a blank as advanced by said pusher device and holding it in upright position within said 10 magazine.

3. In a blank stacking mechanism the combination of a magazine, a rotating helical screw for conveying blanks in spaced upright position 15 toward said magazine, a reciprocating pusher device for engaging behind a said blank as it is conveyed by said screw and moving it into said magazine, and actuating means for swinging said pusher into pushing position behind a blank, for then moving it with the blank toward said magazine, thence swinging it away from said blank and out of the path of travel of a succeeding advancing blank in said helical screw and finally returning it back to position for subsequent blank 20 engagement on succeeding blanks. 25

4. In a blanking machine having a plurality of pairs of cutting dies for severing blanks from opposite sides of a sheet and provided with stacking mechanism comprising, a magazine associated with each pair of dies, a narrow inclined chute leading from a said pair of dies toward an associated magazine and holding said blanks on edge, and feeding means connecting with each chute for successively conveying blanks therefrom and for placing them in stacked formation within 30 its associated magazine. 35

5. In a blanking machine having a plurality of pairs of cutting dies for severing blanks from opposite sides of a sheet and provided with stacking mechanism comprising, a magazine associated 40 with each pair of dies, a chute leading from a said pair of dies toward its associated magazine, said chute being narrow and inclined and holding the blanks on edge, and feeding means connecting with each chute for successively conveying 45 blanks therefrom, and a pusher device associated with each magazine for removing said blanks from said feeding means and placing them in stacked formation within the magazine.

6. In a blanking machine having a plurality of pairs of cutting dies for severing blanks from opposite sides of a sheet and provided with stacking mechanism comprising, a magazine located on each side of the machine, a narrow inclined chute leading from each pair of cutting dies toward a said magazine, said chute being arranged transverse to the magazine and feeding means connected with each chute for successively conveying blanks into the magazines by causing them to travel in the same direction and both toward 55 the same side of the machine. 60

7. In a blanking machine having a plurality of pairs of cutting dies for severing blanks from opposite sides of a sheet and provided with stacking mechanism comprising, a magazine associated 65 with said dies, a narrow inclined chute leading from said dies toward said magazine, and feeding means connected with said chute and operating transversely to the chute and in line with the magazine for successively conveying blanks therefrom and for placing them in stacked formation 70 within said magazine.

8. A blank stacking mechanism having in combination a magazine for receiving the blanks in stacked arrangement, a pusher for advancing 75

blanks in said magazine, a helical conveyer having a wall for advancing blanks to said pusher, and an inclined chute arranged crosswise of the axis of said conveyer for conducting blanks and 5 delivering them to said conveyer.

9. A blank stacking mechanism having in combination a narrow inclined chute for receiving and conducting edgewise a series of cut blanks, a helical conveyer having its axis crosswise of said 10 chute and having a wall for receiving said blanks from the chute and a magazine for receiving said blanks in stacked formation.

10. A blank stacking mechanism comprising in combination a magazine, feeding means including a narrow inclined chute, a helical screw having a wall and operating in a direction crosswise of said chute for conveying single blanks in succession toward said magazine, and a pusher device for moving said blanks away from the 15 discharge end of said screw and for placing them in stacked formation within said magazine, and means for operating the screw and pusher device in timed relation.

11. In a blanking machine having cutting mechanism for severing blanks from sheet material, a stacking mechanism, comprising, in combination: a magazine, feeding means including a rotating helical screw conveyer having a wall, and arranged between said cutting mechanism and 20 said magazine, for conveying blanks in progressive order toward said magazine and for placing them in stacked formation, an inclined chute leading to said screw in a direction sidewise to the axis of the screw, yielding holding devices for 25 engaging the stacked blanks and preventing their movement out of said magazine, a pusher device for moving the said blanks away from the discharge end of the said screw and into said holding device, and means for operating the screw 30 and pusher device in timed relation.

12. In a cutting machine wherein blanks are cut from a sheet at each side thereof, the combination of an inclined chute at each side of said machine, magazines leading from the delivery

ends of said chutes respectively and thence to one side of the machine and having their delivery ends at the same side of the machine, helical stacking conveyers receiving blanks from said chutes respectively, and pushers operating on the 5 blanks respectively delivered by said conveyers to cause the stacks of blanks to progress through said magazines.

13. In a blanking machine having a plurality of pairs of cutting dies for severing blanks from 10 opposite sides of a sheet arranged in substantially level position, and provided with a stacking mechanism comprising a chute for receiving blanks from said dies and inclined backward toward the feeding end of the machine, a magazine extending 15 sidewise under the machine from the lower end of said chute, and a screw conveyor having its wall arranged to propel blanks sidewise from said chute and endwise of said magazine.

14. In a blanking machine having cutting dies 20 for severing blanks from a sheet arranged in substantially level position, a stacking mechanism comprising, a chute for receiving blanks from said dies and inclined backward toward the feeding end of the machine, a magazine extending side- 25 wise under the machine from the lower end of said chute, and a screw conveyor having its wall arranged to propel blanks sidewise from said chute and endwise of said magazine, and a pusher operating in the magazine in the same direction as 30 said screw conveyor.

15. In a blanking machine having a plurality of pairs of cutting dies for severing blanks from opposite sides of a sheet arranged in substantial- 35 ly level position, a stacking mechanism comprising, magazines extending across the machine, chutes having walls arranged to receive and hold the blanks standing on their edges as they come from said dies and delivering the blanks to said magazines, and helical conveyors having walls 40 arranged substantially parallel with the walls of the chutes and operating on said blanks.

JOHN F. PETERS.
